UNITED STATES PATENT OFFICE.

RANDELL HOWARD FLETCHER, OF LLANISHEN, WALES, ASSIGNOR, BY MESNE ASSIGNMENTS, TO THE ALVEY-FERGUSON COMPANY, OF CINCINNATI, OHIO, A CORPORATION OF OHIO.

CONVEYER.

1,065,349.

Specification of Letters Patent. Patented June 24, 1913.

Application filed March 3, 1910. Serial No. 547,098.

To all whom it may concern:

Be it known that I, RANDELL HOWARD FLETCHER, a subject of the King of Great Britain, residing at Llanishen, in the county of Glamorgan, Wales, have invented new and useful Improvements in Conveyers, of which the following is a specification.

This invention relates to improvements in conveyers wherein there are a series of runs having sections extending toward or from a common point which is provided with a switch adjustable to connect one of the first mentioned sections with either one of a plurality of others of the sections.

Conveyers of this type may be variously embodied to accord with requirements, which vary in different installations, as is well known to those skilled in the art, and these various embodiments are contemplated to be within the spirit of my invention and the scope of the subjoined claims, which comprehend as a feature of the invention the employment, in a conveyer of this kind, of a switch mounted to turn in a vertical arc and capable of conducting packages thereover with either of its sides uppermost.

The invention also consists in certain peculiarities in the construction of parts and in certain novel combinations and arrangements of elements substantially as herein described and particularly pointed out in the subjoined claims.

In the accompanying drawings I have illustrated parts of a conveyer at the junction of the runs, showing the preferred form of said parts, but it is to be understood that the particular construction illustrated is merely exemplary and that changes in the construction and in the particularly illustrated arrangement may be made without departing from the spirit of the invention as defined in the claims.

In said drawings:—Figure 1 is a plan view of the portions of the conveyer at the junction of the runs referred to, showing in full and dotted lines respectively the different operative positions of the switch section. Fig. 2 is a transverse section on the line 2—2 of Fig. 1. Fig. 3 is a longitudinal section through the conveyer on the line 3—3 of Fig. 1 looking in the direction indicated by the arrow and showing the switch in a position which it is caused to assume while being turned. Fig. 4 is an end view of the run designated by the letter A, viewed from

the direction of the arrow. Fig. 5 is a similar view of either of the other runs.

The same characters of reference designate the same parts in the several views.

A conveyer or conveying system constructed in accordance with the present invention comprehends as one of its leading features a reversible run or section, as D, so mounted that it may be turned on an approximately horizontal axis which is disposed off the center of the run or section, and other package-supporting members, as A, B and C, relatively so disposed as to co-operate with the different operative surfaces of the reversible section or run. 70

It further comprehends, as an additional leading feature thereof, a relation of the members A, B and C with respect to the reversible run or section D, such that the axis of turning movement of the last-named section will be on a line which bisects the end of the member A and a junction between adjacent sides of the members B and C, the correlation of the parts being such that the reversible run or section forms, for example, a continuation of the member A and may be turned on its said axis from a position in which it connects the member A with the member C to one in which it connects the member A with the member B. 80 Each of the members A, B and C is preferably a package-conveying section, but in some installations, or in parts of a system, all of said members need not be used, and if three members are used in connection with the switch, all of said members need not be conveyers in the true sense of the word. 85

There are other and further important features of the invention in respect of the construction and relative arrangements of the parts, which will hereinafter fully appear. 95

In the accompanying drawings the preferred detail embodiment of the invention is illustrated. In this embodiment each of the runs or sections A, B and C are of the gravity roller type, and this is also true of the reversible section D. Only the ends of the runs or sections A, B and C are shown, it being of course understood that said sections are of any suitable length and extend from different places toward a common point, in which the reversible switch section D is located. In the illustrated embodiment, the ends of the sections B and C curve 100

105

110

toward each other. It will be understood that the conveyer system may be provided at different places with runs arranged at an angle with each other, and that in such case there will be a switch D at each of the junctions.

In the illustrated embodiment of the invention: each of the runs is provided with a frame preferably having side members 10 and 11 formed of angle irons arranged longitudinally thereof, and transverse strips 12 spaced apart and connecting the angle irons. Each frame is erected upon suitable supports which may be composed of legs 13 connected and braced by cross braces 14. The frame is also preferably provided with other longitudinal angle irons 15 which serve as guard rails and are carried by brackets 16.

The several parts of the frame are riveted or otherwise secured together at their intersections. The side-members 10 and 11 provide bearings for the journals 17 of the freely-rotatable rollers 18 which form the bed of the conveyer.

The illustrated form of the switch-section D comprises a frame having concentrically curved longitudinal sides 20 connected at one end by an integral transverse piece 21, and connected at its other end by a separately formed transverse piece 22 secured to bent ends 20¹ of said sides 20. The curved sides 20 provide bearings for the journals 23 of freely-rotatable rollers 24 which form the bed of the way and are of sufficient diameter to extend beyond the upper and lower edges of the frame so that packages may be conducted thereon with either side of the switch section uppermost. Guard rails 25 are provided on both sides of the switch section above and below the rollers and are preferably supported by brackets having a U-shaped portion 27, riveted or otherwise secured to the frame-members 20, and oppositely extending flanges 28 secured to the guard rails.

The ends of the runs B and C extend curvilinearly in different directions from a junction between the extremities of their corresponding side-members 10. As these side members meet or approximately meet at said place it will hereinafter be referred to as "a junction." It will be noted that this junction is arranged at a point approximately in alinement with the transverse center of the run A. At said junction there is preferably shown a bracket 29 or other suitable means for connecting these members 10 with each other.

To allow the switch D to swing in a vertical arc to connect the runs A, with the ends of either of the runs B and C, one of its ends is provided with a pivot-pin (or trunnion) 30, arranged at or contiguous to the junction of its frame members 20 and 22 and journaled in the bracket 29, and its other

end is provided with a pivot-pin (or trunnion) 32 projecting from its member 21 approximately in line with the transverse center of said member and journaled in a bracket 31 secured approximately at the transverse center of the run A. Stops or supports 33 and 34 for the switch-frame are secured to the extremities of the side members 11 of the ends of the runs B and C, respectively.

The switch D when in operative position is supported at three points having a triangular relation with each other, to wit, the pivot-pins 30 and 32 journaled in the brackets 29 and 31 and the corner of the switch frame which rests upon one of the stops 33 or 34. The stability of this construction will be manifest.

It will be noted that the axis of turning movement of the switch section is such that the center of gravity is not in alinement with the axial center of the switch section. A weight 35 is therefore provided to counterbalance the weight of the heavier side of the section. This weight is preferably secured to the guard rail 25 near one end thereof.

In Fig. 1 the switch-section D is shown in full lines in position to connect the run A with the curved end of the run C, the edge of the switch-frame at a corner thereof resting upon the support 34 at the extremity of the side-member 11 of the run C, with the ends 21 and 22 of the switch-frame in alinement with the contiguous ends of the runs A and C respectively, while in dotted lines is shown the position the switch is caused to assume to connect the run A with the run B. To throw the switch from one operative position to the other, the section D is turned on the pivots 30 and 32 throughout a semicircular arc, moving the corner of the switch frame from the support 34 at the extremity of the side member 11 of the run C until its opposite edge contacts with the support 33 carried by the side member 11 of the run B. In this position the ends 21 and 22 of the switch are in alinement with the ends of the runs A and C respectively.

It will be noted that one end of the switch D will always be in alinement with the run A, while the opposite end of the switch may be swung into alinement with either of the curved ends of the runs B, C, and that the switch is a reversible one, being operative to convey packages thereover with either of its sides uppermost.

It frequently is desirable in gravity conveyers to temporarily stop the feeding of packages therefrom without stopping the supply of packages to the conveyer. It will be noted that the switch D provides a convenient means for this purpose for the reason that when in a raised position its end

21 will be interposed in the path of a package on the run A, stopping the movement of said package and through the medium of the latter barring the movement of following packages from the run A. If either 5 of the other runs or sections of the conveyer lead to a shipping point, or to an elevator, or to a lowerer, for example, and it is not convenient to have the packages run thereto, they may be temporarily cut out by 10 movement of the switch to the described position.

From the foregoing the construction, operation and advantages of my invention will 15 be understood and it will be apparent that the invention is not restricted to the detailed embodiment illustrated in the accompanying drawings, but may be widely varied in respect of said details and variously embodied 20 in conveyers of different types, gravity and otherwise.

While it is considered unnecessary to explain herein the different embodiments to which the invention lends itself, yet in a 25 general way, it may be stated that in conveying systems as frequently embodied, runs of gravity or other nature are employed in connection with elevators, or with spiral lowerers, for conveying the packages from 30 one floor or level to another, and systems of this kind, as well as those wherein the packages are conveyed only on a level, may include the herein described switch means.

Having now described the invention what 35 I believe to be new and desire to secure by Letters Patent is:—

1. A package conveyer, comprising a reversible run or section which is mounted so that it may be turned on an approximately 40 horizontal axis disposed off the center of the run or section, said run or section having opposite conveying surfaces, and package-supporting members relatively arranged to be joined by the respective conveying surfaces of the reversible section or run, the 45 package-supporting members comprising package-feeding means.

2. A package-conveyer comprising package-supporting members extending toward 50 a common point, and a reversible run or section which is mounted to turn from an operative relation with one of said members into operative relation with the other, on an approximately horizontal axis disposed off of the line of the transverse center of the 55 reversible run or section and in a line which bisects the space between adjacent sides of said members at the ends of the latter contiguous to the reversible run or section.

60 3. A package-conveyer comprising a series of package-supporting members, two of which have their sides which confront each other arranged contiguous to a place which is opposite the transverse center of the third member, said third member being spaced 65

from the ends of the other two members, and a reversible section or run mounted to turn on an approximately horizontal axis in said space to operatively connect either of the first two members with the third member, 70 said reversible section or run having its axis in line with the transverse center of the third member and the space separating the sides of the first two members from each other. 75

4. A package conveyer comprising a pair of members having ends which are arranged side by side, a third member spaced from said pair of members and having the transverse center of its ends arranged in a line 80 which bisects the space separating contiguous sides of the first two members from each other, and a fourth member mounted to turn on an approximately horizontal axis and adapted to convey packages between the 85 third member and either of the first two members, said fourth member being pivoted at one end in line with the transverse center of the third member and having its other end pivoted at a place which is off of 90 its transverse center and bisects the space between adjacent sides of the first two members.

5. A package conveyer comprising two package conveying sections each comprising 95 a bed or way, the ends of said sections being spaced apart and disposed in such relative positions that their transverse centers will be out of line with each other, and a switch section which is mounted to turn on 100 an approximately horizontal axis between said ends and has a bed or way which forms a continuation of the beds or ways of the latter when it is in one position of its adjustment, the axis of turning movement of 105 the switch section being off the line of the transverse center of its bed or way and in a line which bisects the end of the bed or way of one member and is adjacent to an edge of the bed or way of the other member. 110

6. A conveyer comprising a series of runs, the ends of two of which have contiguous sides, and the other of which runs is spaced from said ends, combined with a reversible conveying section which is arranged in said 115 space and adapted to connect the third run with the ends of either of the two runs first mentioned, said reversible run being pivotally mounted at a plurality of places to turn on an approximately horizontal axis 120 which is off the line of the transverse center of said section, one of said pivots being disposed in proximity to the transverse center of the end of the third run and the other of the pivots being in proximity to the junction 125 of adjacent sides of the other runs.

7. A conveyer comprising a run, a plurality of other runs having curved ends which extend toward each other, corresponding sides of said ends being arranged 130

to form a junction disposed approximately in line with the transverse center of the end of the first-mentioned run, said run and ends being spaced apart, and a reversible 5 section adapted to connect the first-mentioned run with either of said curved ends, said section having one of its ends in line with the end of the first-mentioned run, and the junction of its other end and a side 10 arranged contiguous to said junction of the curved ends, and being mounted to turn approximately perpendicularly to the plane of the other runs to align its last-mentioned end with either of said curved ends, upon 15 fulcrs disposed in proximity to said junction and the transverse center of the first mentioned run, respectively.

8. A conveyer having separated members, one of which is provided with feeding means, 20 and a pivotally mounted section arranged in the space between the ends of said members and forming a combined switch and stop, the said section having a surface adapted to convey packages from one of said members 25 to the other and having its axis so disposed that its end which is arranged adjacent to the member having feeding means will project above the latter so as to bar the progress of a package therefrom when said section is 30 turned from its conveying position.

9. A conveyer having separated members provided with means for feeding packages thereon, a separate section arranged in the space between the ends of said members and 35 having means for conveying packages from one of said members to the other, said section being pivotally mounted at its opposite ends to turn upon an approximately horizontal axis, the pivot at one end of the section being arranged between the sides of 40 the section, and approximately in line with the transverse center of the adjacent member, and also so disposed with relation to the conveying surface of said section and 45 the conveying surface of the adjacent member that the end of the section will project above the surface of the latter member and bar the progress of a package therefrom when the section is turned from its conveying 50 position.

10. A package-conveying means having a plurality of runs each comprising a frame provided with a package-supporting bed or way and a switch section mounted to turn on 55 a horizontal axis and having a package-supporting bed or way adapted to form a continuation of the bed or way of either of said runs, said switch section being fulcrumed off the line of its transverse center.

60 11. A conveyer comprising a plurality of package-conveying members and a third member having a series of package-feeding rollers forming its bed, said third member disposed in such relation with the ends of 65 the other members as to be movable piv-

otally in a vertical plane into operative relation from one to the other and having its rollers so disposed as to operate when either of its sides is uppermost.

12. A conveyer comprising a plurality of 70 package-conveying members having converging curved sections, sides of which approximately meet at the extremities thereof, and a third member having a series of package-feeding rollers forming its bed, said third member being fulcrumed at its opposite ends, one of its fulcrums being in proximity to the junction of said sides of the curved section.

75 13. A conveyer comprising a plurality of runs, provided with curved ends having sides which approximately meet at the extremities thereof, a separate run which is spaced from said ends and is arranged with the transverse center of its end approximately in line with the junction of said sides, and a reversible switch having a series of package-feeding rollers forming its bed, said rollers so disposed as to operate when either side of the switch is uppermost, said switch being fulcrumed at opposite ends in proximity with said junction and the transverse center of the second-mentioned run, respectively.

80 14. A conveyer having a plurality of members extending toward a common point, and a reversible switch having a pivotal support off its center and movable into operative relation with either of said members, and a balance weight for said switch.

85 15. A conveyer having a plurality of members extending toward a common point and provided with sides which approximately meet at the extremities thereof, a switch adaptable to either of said ends, said switch pivotally mounted off the line of its longitudinal center, in proximity to the junction of said sides and provided with a balance weight, and elements coöperating with the pivot for supporting the switch in 90 its adjusted positions.

95 16. A conveyer having a plurality of members extending toward a common point and provided with sides which approximately meet at the extremities thereof, a switch adaptable to either of said sides, said switch pivotally mounted at a corner thereof in proximity to the junction of said sides and provided with a balance weight, and elements at the extremities of the other sides 100 of said members for supporting the movable corner of the pivoted ends of the switch.

105 17. A conveyer having a plurality of members extending toward a common point and provided with sides which approximately meet at the extremities thereof, another member spaced from the same and disposed with the transverse center of its end in approximate alignment with the junction of said sides, and a reversible 110

115 120 125 130

- switch mounted in said space and so related to said members as to be adapted to connect either of those first-mentioned with the other one, one end of said switch being pivoted at one corner in proximity with the junction between said sides and the other end thereof being pivoted in proximity to its transverse center and the transverse center of the other run, said switch having a balance weight, and the other sides of the first-mentioned runs having supporting elements for the movable corner of the eccentrically pivoted end of the switch.
18. A conveyer having a plurality of runs provided with contiguous ends, and a reversible switch so disposed with relation to said ends as to swing in a vertical plane from operative relation with one into operative relation with the other, said switch having package feeding rollers in its bed and guard rails arranged above and below the plane of said rollers.
19. A conveyer having a plurality of runs provided with contiguous ends, a reversible switch so disposed with relation to said ends as to swing in a vertical plane from operative relation with one into operative relation with the other, said switch having package feeding rollers in its bed and guard rails arranged above and below the plane of said rollers, combined with a third run, so disposed with relation to the contiguous ends of the switch as to be operatively related thereto when the switch is in either of its package-feeding positions.
20. In a conveyer, runs having curved
- ends, sides of which are relatively disposed to form a junction, a reversible curved switch pivotally mounted in such relation to said junction as to swing in a vertical plane 40 from operative relation with one of said runs into operative relation with the other of the same, said switch having package feeding rollers in its bed and guard rails arranged above and below the plane of said 45 rollers.
21. In a conveyer a pair of runs having curved ends arranged in proximity to each other, a third run the end of which confronts the curved ends of the other runs and 50 is spaced therefrom, and a reversible curved switch pivotally mounted in said space, with one of its ends in such relation with said curved ends that it will turn in a vertical plane from feeding relation with one of 55 said ends into feeding relation with the other of the same, and at its other end pivotally mounted in such relation with the contiguous end of the third run as to be in feeding relation therewith when in either 60 of its feeding positions, said switch having package feeding rollers in its bed and guard rails arranged above and below the plane of said rollers.
- In testimony whereof I have hereunto set 65 my hand in the presence of two subscribing witnesses.

RANDELL HOWARD FLETCHER.
